VALVE FOR INTERNAL COMBUSTION ENGINES

George L. Ellis, Tillamook, Oreg.

Application June 9, 1936, Serial No. 84,337

6 Claims. (Cl. 123—81)

This invention relates to valves for internal combustion engines and is particularly adapted to automobiles, tractors and truck motors.

The primary object of this invention is to provide a valve that will not have to be ground after it is once fitted to the seat because it is a self-seating type of valve thereafter.

Another object of the invention is that it enables the combustion chamber to be directly over 10 the piston head.

Further object of the invention is that there is no adjusting of tappets required after the valves have once been timed to the motor.

A further object of the invention is that due to 15 the design of the valves the ports can be opened and closed rapidly.

And a still further object of the design of this valve is that it is self-adjusting at all times in regards to clearance, due to expansion and contraction.

These and other incidental objects will be apparent in the following specification and claims.

Referring to the drawing:

Figure 1 is a side elevation of a motor, partially 25 broken away, having my new and improved valves installed therein.

Figure 2 is an end sectional view, partially 30 broken away, of Figure 1, taken through the exhaust valve port showing the exhaust valve closed.

Figure 3 is a fragmentary sectional view taken through the intake port, showing the valve in open position.

Figure 4 is a perspective end view of one of my 35 new and improved valves.

Figure 5 is a sectional end view of the valve assembly support and adjusting means, taken on line 5—5 of Figure 1.

Figure 6 is a fragmentary side view of the valve 40 supporting bar.

In the drawing:

1 is an internal combustion motor, having the usual cylinders 2, pistons 3 and connecting rods 4. The combustion chamber is indicated at 5. Each of the cylinders have one exhaust valve 6 and one intake valve 7. These valves are mounted upon a shaft 8 running longitudinally of the motor. The shaft 8 is fixedly mounted upon the bar 9 by upwardly extending bearing supports 10. The valves 6 and 7 have bearing sleeves 11 within the downwardly extending legs 12 forming a bearing support for the main body 13 of the valve. The valves consist of half or semi-circle bodies, having counter sunk portions 14, which

provide a by-pass for the gases when registered with the proper ports.

Referring to Figures 1, 2 and 3. In Figure 3 the intake valve is shown open. The counter sunk portion being registered with the intake port 15 from the fuel supply, not here shown, and the port 16 leading to the combustion chamber 5. The valve was placed in this position by the cam shaft 17 actuating the push rod 18, contacting the under side 19 of the valve with its rounded bearing end 20. At the same time the push rod 21 was forced downward against the spring tension 22 which will return the valve to the starting position when the push rod 18 is allowed to lower by the action of the cam 17.

Referring to Figure 2, the valve 6 is shown having the counter sunk portion 14 out of registry with the ports 23 and 24 of the exhaust line. The valve operating mechanism is the same as heretofore described. The valve bodies have 20 flanged ends 25 which fit into grooves 26 of the block and tend to seal the gases within the chambers. These flanges are tapered, best shown in Figure 1 at 27, therefore they are self-sealing when the valve body is forced upward into the 25 block.

The valve supporting bearing shaft 8 is drilled for the passage of oil as shown at 28. The valves have oil passageways 29 for directing the oil for lubrication purposes over the surfaces of their 30 seats by the grooves 30. In order to remove the valve assembly or replace it the push rods 18 and 21 are removed from the motor by removing the screw 31 and cap 32 of the valve guide supports 33. The valve assembly supporting bar 9 rests 35 in the floating adjustable bearing blocks 34 and 35, one of these sets of blocks being located on either end of the motor within the housings 36 and 37. Adjusting bolts 38 and 39 center and adjust the blocks 34 and 35 so that the bearing supporting bar 9 will be in the proper position relative to the valves and their seats. The bearing blocks 34 and 35 straddle the end 40 of the bar 9. The adjusting screws 38 extend part way into the blocks having a flexible element 41 directly in contact with the block and against the shoulder 42 of the adjusting screw. This flexible element permits a limited movement to take care of expansion and contraction of the valve assembly 45 and is very important. In order to remove the valve assembly, as stated before, the valve push rods are first removed after which the bars 44 are removed allowing the bearing block and the valve supporting bar 9 to be pulled towards the 50 55

left of Figure 5 and the whole assembly dropped down and out through the side of the motor after the plate 45 has been removed.

I do not wish to be limited to this particular form of construction as my invention may take other mechanical embodiments still coming within the scope of the claims.

What is claimed to be new is:

1. An internal combustion engine having a valve chamber formed with a plurality of semi-cylindrical valve seats arranged in pairs for each cylinder, a semi-cylindrical valve cooperating with each seat, said valve being formed with a peripheral depression, the inlet port and exhaust port of each cylinder being closed when the valve is in one position and opened through the depression in the valve when the valve is in another position, a shaft for supporting all the valves, and removable means for supporting the shaft, said means including a bar terminally extended beyond the valve chamber and means for adjusting the bar vertically to thereby maintain appropriate contact between the valves and their seats.
2. A construction as defined in claim 1, wherein the bar adjusting means is constructed to automatically compensate for expansion and contraction of the valve assembly.
3. A valve mechanism for internal combustion engines, including a valve chamber formed with a plurality of semi-circular valve seats arranged in pairs for each cylinder, a valve supporting bar extending lengthwise the valve chamber and beyond the ends of said chamber, means beyond each end of the valve chamber for vertically adjusting the bar, a shaft supported by the bar within the valve chamber, a series of valves supported for rocking on said shaft, said valves operating accurately with the respective valve seats, with each valve sealed against the adjacent valve, the periphery of each valve being formed with a depression, the inlet and exhaust ports from the cylinders opening through the respective valve seats and being closed by the normal periphery of the valve and opened through the de-

pression in the valve, a cam-operated valve stem for each valve and operative under the influence of the cam to rock the valve to a position to cause the depression in the periphery thereof to open the particular port, a spring-pressed valve stem 5 cooperating with each valve and operating the valve when free of the influence of the cam-operated stem to a position to cause the normal periphery of the valve to close the particular port, and means in the valve chamber for removably 10 supporting the respective valve stems for each valve.

4. A construction as defined in claim 1, wherein the valve adjusting means includes blocks embracing the ends of the bar and means for adjusting the blocks toward and from each other, said adjusting means being yieldingly connected with the blocks to permit expansion and contraction.

5. In combination, an internal combustion engine formed with a valve chamber and with a cylinder service port, the continuity of the service port being interrupted at the margin of the valve chamber to provide two distinct sections of such port, both of which open into the valve chamber, a rocking valve mounted in the valve chamber and formed with a cylindrical surface to accurately fit the valve chamber and with a flat side, means for pivotally supporting the valve in the plane of the flat side, an element free of connection with the valve and bearing on the flat side in one direction beyond the pivot, and means bearing on the flat side in the opposite direction from the pivot to normally maintain a closed position of the valve with respect to the cylinder service port, the operating means serving to move the valve to cause the valve depression to register with both sections of the service port to complete the continuity thereof.

6. A construction as defined in claim 5, wherein the means for operating the valve is longitudinally adjustable to control the accuracy of valve movement in establishing communication between the sections of the service port.
